By J. Jochum Esq. Atty.

UNITED STATES PATENT OFFICE.

JACOB MANDEL, OF CHICAGO, ILLINOIS, ASSIGNOR TO WELLINGTON-STONE COMPANY, INC., OF CHICAGO, ILLINOIS, A CORPORATION OF ILLINOIS.

DESIGN FOR A LAMP BASE.

Application filed May 11, 1925. Serial No. 13,401. Term of patent 3½ years.

To all whom it may concern:

Be it known that I, JACOB MANDEL, a citizen of the United States, residing at Chicago, in the county of Cook and State of Illinois, have invented a new, original, and ornamental Design for Lamp Base, of which the following is a specification, reference being had to the accompanying drawing, forming a part thereof.

In the drawing:

Figure 2 is a top plan view of the base showing only a portion of the ornamental features thereof completed, it being understood that the balance of the unfinished portion is a mere repetition.

I claim:

The ornamental design for a lamp base as shown.

JACOB MANDEL.
